tion of Wisconsin

Application February 19, 1945, Serial No. 578,572

13 Claims. (Cl. 134—80)

1

The present invention relates to apparatus for conditioning containers and more particularly containers in the nature of barrels or the like.

Among the objects of the present invention is to provide a novel device for conditioning containers, such as barrels or the like, expeditiously, economically and effectively.

For some time in the past it has been the practice, particularly in the petroleum field, to make use of barrels for holding oil and the like for one shipment of such goods and to then junk or destroy the same. However, due to present economic conditions, barrels cannot be easily secured and it has become the general practice in the trade to recondition these barrels after use so as to be re-usable again and again for shipment of the particular products desired. Because of the nature of the products involved, it has been exceedingly difficult to condition the barrels for such successive uses and to provide containers which are uncontaminated with the material previously shipped therein and resort has been made to extensive hand operations which, under present circumstances, is exceedingly undesirable and unsatisfactory, as well as making the cost of such reconditioning excessive.

One of the principal objects of the present invention is to provide a novel container conditioning apparatus which can be operated by relatively unskilled labor at relatively low cost for effectively and efficiently treating such barrels or containers to make them suitable for re-use after each shipment. In this aspect of the invention, barrel equipment may be re-used time and again, thus greatly decreasing the cost of shipment of such goods as are particularly found in the petroleum field.

Another object within the purview of the present invention is to provide a novel container conditioning apparatus which by simple manipulation is adapted to cyclically treat successive barrels introduced therein through a complete conditioning operation involving, for example, such steps as applying a caustic material to the interior and exterior surfaces of such containers, draining such caustic material from the containers, rinsing the same with wash water, and then causing the containers to be dried by the application of air, or the like, thereto.

In the more particular aspects of the invention, one object thereof is to provide a conveyor system for the said containers so constructed and arranged as to facilitate the operations above referred to and which procedures involve the supplying of such fluids as are desired for the

conditioning operations to the containers by gravity flow, both to the exterior and interior surfaces of the containers. In this connection, the invention further contemplates the application of heated air to the fluid flow into the interior of the containers so as to effectively disperse the same over the entire interior of such containers to assure proper conditioning thereof.

Still another object of the present invention is to provide a novel arrangement for raising the temperature of the conditioning fluids, involving the use of heater tubes adapted to discharge spent gases of combustion into a flue associated with a distributor head for the air such that the temperature of the air is elevated the desired amount.

Still another object of the present invention is to provide a novel housing structure for the containers undergoing treatment, comprising a movable buoyant support for such containers adapted, when in normal initial position or in the absence of fluid within the housing, to dispose the containers in a position inclined toward the entrance to the housing so as to facilitate introduction of the containers therein and to provide for effective draining of the containers, yet which is adapted under the buoyant action of fluid when in the housing to move such containers into substantially an upright position whereby conditioning fluid effectively treats the exterior surface of such containers.

The invention further comprehends the idea of incorporating vibrating means for the containers within the housing structure so as to assure dislodgement of material adhering thereto during the conditioning process.

Other objects, features, capabilities and advantages are comprehended by the invention, as will later appear and as are inherently possessed thereby.

Referring now to the drawings, Figure 1 is a top plan view of conditioning apparatus made in accordance with the present invention;

Figure 2 is a view in front elevation of the device disclosed in Figure 1 of the drawings;

Figure 3 is a fragmentary view in cross section taken in the plane represented by line 3—3 of Figure 1 of the drawings;

Figure 4 is a fragmentary view in cross section taken in the plane represented by line 4—4 of Figure 3 of the drawings; and

Figure 5 is a view in cross section taken in the plane represented by line 5—5 of Figure 4 of the drawings.

Referring now more in detail to the drawings,

2

10 to provide a novel arrangement for raising the temperature of the conditioning fluids, involving the use of heater tubes adapted to discharge spent gases of combustion into a flue associated with a distributor head for the air such that the temperature of the air is elevated the desired amount.

20 Still another object of the present invention is to provide a novel housing structure for the containers undergoing treatment, comprising a movable buoyant support for such containers adapted, when in normal initial position or in the absence of fluid within the housing, to dispose the containers in a position inclined toward the entrance to the housing so as to facilitate introduction of the containers therein and to provide for effective draining of the containers, yet which is adapted under the buoyant action of fluid when in the housing to move such containers into substantially an upright position whereby conditioning fluid effectively treats the exterior surface of such containers.

25 The invention further comprehends the idea of incorporating vibrating means for the containers within the housing structure so as to assure dislodgement of material adhering thereto during the conditioning process.

30 Other objects, features, capabilities and advantages are comprehended by the invention, as will later appear and as are inherently possessed thereby.

35 Referring now to the drawings, Figure 1 is a top plan view of conditioning apparatus made in accordance with the present invention;

40 Figure 2 is a view in front elevation of the device disclosed in Figure 1 of the drawings;

45 Figure 3 is a fragmentary view in cross section taken in the plane represented by line 3—3 of Figure 1 of the drawings;

Figure 4 is a fragmentary view in cross section taken in the plane represented by line 4—4 of Figure 3 of the drawings; and

Figure 5 is a view in cross section taken in the plane represented by line 5—5 of Figure 4 of the drawings.

Referring now more in detail to the drawings,

50

an embodiment selected to illustrate the present invention is shown as comprising a circular type conveyor 2 formed with a plurality of housing structures 4, each of which is provided with a caster 6 operating over the circular track 8, whereby each of the housing structures may be progressively moved through a conditioning cycle of operation for containers which may be disposed within such housing structures.

The housing structures are interconnected by members 10, apertured as at 12, whereby the conveyor can be rotated as above explained by the introduction of a tool into the opening 12 by the operator. Interconnecting the housing structures at their tops is a fluid receiver 14 of annular construction, partitioned as at 16 on each side of the housing structures for a purpose which will be understood more clearly as the description proceeds.

According to the embodiment herein disclosed, the arrangement of the mechanisms is such as to particularly adapt the same for use in conditioning barrels 18, as shown in Figure 3 of the drawings, which are formed with bung-openings, such as 20, disposed in one of the end walls of the barrel and adjacent the chime 22. This type of barrel inherently possesses a structure which is difficult to effectively condition and accordingly the present apparatus has incorporated therein certain features of construction which facilitate the handling and conditioning of this type of barrel, although it is to be understood that the same may be used for conditioning containers generally.

While reference has been made to the housing structures by the reference numeral 4, it is to be noted that in accordance with Figure 1 the present device has eight of such housings all of the same construction and which for convenience in the further description of the procedures involved will be referred to as being disposed in the various positions of the conditioning cycle A, B, C, D, E, F, G, and H.

As shown in Figure 1, the housing structure A is disposed opposite the filling station at which point one of the barrels may be introduced therein by an operator standing in front of the machine. By introduction of a tool into the opening 12, the conveyor 2 may be rotated by successive steps to position successive housing structures in position at the filling station. Furthermore, in accordance with the procedures herein described in connection with the conditioning of the barrels 18, housing structures B and C are positioned to have a caustic solution directed onto the interior and exterior surfaces of the barrels disposed therein. The housing structure D is representative of the position which each successive housing structure takes for the draining of the caustic solution from the housing after the barrels have been treated thereby. Housing structure E is representative of the position which the housing structures assume during the introduction of a rinsing solution, such as water, after which such water is allowed to drain from the housings when in the position represented by the housing structure F. Housing structures G and H are representative of the positions which each successive housing structure takes during the cycle of operation when warm air alone is introduced into the housing structures for drying the barrels.

Since each of the housing structures 4 is of similar construction, as more particularly shown in Figure 3 of the drawings, reference will be

made to one only as to its detailed construction for the purposes of this illustration. The housing structure 4 is of general elongated formation comprising side walls 24 and 26 interconnected by the circular end wall 28 and defining a chamber 30 of the proper size to receive the barrel 18 to be conditioned. The front of the housing structure is provided with a slide frame 32 adapted to receive a closure member 34 which is raised and lowered through the handles 36 whereby the barrel 18 may be introduced into and removed from the chamber 30.

The receiver 14 is connected to the upper inner margins of the housing structures and is formed with oppositely disposed baffles 38 for directing fluid through a discharge pipe 42 into the upper region of the chamber 30. The chamber 30 immediately below the discharge pipe 42 is partitioned by the baffle 44, apertured as at 46, to permit the fluid to flow by gravity onto the upper end surface of the barrel and about its side wall surfaces. In order to properly control the dispersion of the fluid, baffle member 48 defines the marginal edge of the opening 46 adjacent the discharge 42. In order to control the upward dispersion of the fluid introduced into chamber 30, baffle plate 50 is provided to provide a tortuous passage of the air through the opening 46 to the atmosphere through the opening 54 in the top or end wall of the housing. Depending flange or baffle 52 is also provided at one side of opening 54.

The receiver 14 is further provided with a discharge conduit 56 extending downwardly on the inside of the housing structure and which has the horizontal extension 58 terminating in the vertical fitting 60 disposed within an outer fitting 62 attached to the air distributing conduit 64, one end of which leads into the housing structure from the rotatable distributor head 66 of the air supply system.

The fitting 62 extends upwardly beyond a support 68 for the barrel 18 and when the barrel 18 is introduced into the housing structure, the bung-opening 20 is inserted over fitting 62 so that conditioning fluid is introduced into the barrel from receiver 14 by gravity flow to the fitting 60, at which time the same is acted upon by air under pressure flowing through fitting 62 to disperse the same for effectively covering the entire interior surface of the barrel being treated.

The support 68 is characterized as including a pivotal support, as at 70, in the side walls 24 and 26 of the housing structure and the float members 72 and 74 which, under the action of fluid in the conditioning operation, cause the support to be moved from its dotted line position to that shown in full line position in Figure 3 of the drawings. Accordingly, it will be apparent that at the filling station A the support is disposed in such a position as to facilitate introduction of the barrel 18 into the housing structure. When the barrels are treated at stations B, C and E, the support is moved about its pivot point 70 to move the barrel into a substantially upright position, thus facilitating the dispersion of fluid to all parts of the exterior surface. At the remaining stations during the cycle of operation, the tilting of the support as shown in Figure 3 of the drawings provides a convenient way of completely draining the conditioning fluid from the barrels through the bung-opening 20.

In order to facilitate the proper treatment of the end of the barrel adjacent the support 68, the

distributor conduit 58 is provided with a plurality of jets 76 adapted to project conditioning fluid to the end wall of the barrel undergoing treatment.

The lower end of each of the housing structures is provided with a chamber 71 adapted to collect the conditioning fluid for raising the float members 72 and 74, the conditioning fluid being discharged through the discharge 78 into the annular shaped collector 80 which returns the conditioning fluid to the tanks or reservoirs holding the same, as through the discharge 82 shown in Figure 3 of the drawings.

As previously described, the conditioning fluids used in accordance with the present disclosure consist of caustic solution and rinsing water and, accordingly, the reservoirs or tanks for such material are shown at 84 and 86, respectively, both of which are of substantially the same construction and are disposed in substantially opposed relation below the track or support 8 for movement of the conveyor. Each of the tanks is provided with a plurality of baffles, such as 88, adapted to provide a circuitous path for the fluid being used. Disposed within the tanks are a plurality of heater tubes 90 at the end of each set of which is provided a burner 92 for raising the temperature of the conditioning fluid. Each of these heater tubes extends through the end walls 94 of the tanks and is adapted to discharge the products of combustion into a central flue 96 defined at its top by the cylindrical wall 98 for discharging such products of combustion directly beneath the distributor head 66 of the air supply system. Distributor head 66 is provided with depending structure, generally represented as 100, embracing the cylindrical wall 98 of the flue and which is further provided with a plurality of lateral openings 102 adapted to permit the escape of these spent gases upwardly through the central portion of the device.

In circulating the caustic solution through the system, use is made of a centrifugal pump 104 operated by the motor 105, the pump having an intake 106 into the tank 84 and a discharge conduit 108 extending up and over the conveyor and being provided with discharge nozzles 110 and 112 disposed to simultaneously introduce caustic solution into the space between adjacent partitions 16 of the receiver 14 when the housing structures are moved into positions B and C. In order to prevent loss of caustic solution and its dispersion onto parts of the equipment which might be damaged, a plate 114 is secured to the discharge nozzles 110 and 112 over that portion of the receiver into which caustic solution is being discharged.

The rinse water is similarly introduced into the receiver 14 when the barrels are moved into the position E through the medium of a centrifugal pump 116 operated by the motor 117, the pump having an intake 118 into the tank 86 and having a discharge conduit 120 extending up and over the conveyor and discharging into the receiver 14 through the discharge fitting 122.

The air supply is constituted by a blower 124 operated through the medium of a motor 126 and which blower 124 delivers air through the conduit 128 extending up and over the conveyor and which is connected to a centrally disposed conduit 130 connected to the distributor head 66 through the slip joint 132 whereby the distributor head 66 can rotate in accordance with the movement of the conveyor.

In order to assure complete removal of conditioning fluid from the upper end of the barrels

18, a suction device is provided for each of the housing structures consisting of a flexible tubing 134 having a hooked conduit 136 adapted to fit over the chime of the barrel to remove any residual conditioning fluid disposed therein. This flexible tubing 134 is connected with a fitting 138 extending through the wall 24 of the housing structure which is connected to conduit 140 leading to and being connected with a conduit 142 which has its inner end terminating within a conduit 144 constituting a supplemental or auxiliary discharge for conditioning fluid from the next adjacent housing structure whereby discharge of fluid therefrom creates a vacuum through the vacuum system above recited for drawing water from the chime end of the barrel.

During the operation of the conditioning apparatus as above described, it is to be noted that the circulatory systems for the caustic solution and rinsing water are continuously in operation to provide the necessary conditioning fluid for the process involved, which said conditioning fluids in both instances are supplied to the barrels by gravity flow. The air system is likewise continuously operated and is effective through the fittings 62 in dispersing the conditioning fluids at the stations B, C and E and in facilitating the draining and drying of the barrels when in the remaining positions as shown in the drawings.

In order to assure the dislodgement of material adhering to the barrels during the conditioning operation, a cam 146 is provided on the shaft 70 in association with each of the supports 68 and which cam through the medium of a motor 148 secured by bracket 150 to the exterior of the housing is adapted to rotate and intermittently engage the lower-most end of the barrel for the purposes described.

The container conditioning device above described is characterized by the simplicity of its construction, ease of manipulation, and particularly by the fact that conditioning of the containers is effectually secured without the incorporation of high pressure fluid mechanisms which present difficult maintenance problems with attendant high cost of operation.

While I have herein described and upon the drawings shown an illustrative embodiment of the invention, it is to be understood that the invention is not limited thereto but may comprehend other constructions, arrangements of parts, details and features without departing from the spirit of the invention.

What is claimed is:

55. 1. In a washing device, the combination of a conveyor having means providing a movable buoyant support for containers having an opening into the interior thereof and providing for a normal initial inclined disposition of said containers, means for supplying fluid for conditioning said containers, a fluid receiver disposed above said conveyor means for delivering said conditioning fluid from said means for supplying fluid to said receiver means for delivering said conditioning fluid by gravity flow from said receiver to the exterior and interior of said containers, said last named delivery means including means projecting into said containers through the openings therein, means for delivering air under pressure adapted to act upon said fluid delivered to the interior of said containers for dispersing the same over the interior surfaces of said containers, and means providing for the return of said conditioning fluid to said supply means after a conditioning operation, said last-named means

being so constructed and arranged as to provide for the movement of said buoyant support under the action of said conditioning fluid to move said containers into a substantially upright position during a conditioning operation.

2. In a washing device, the combination of a circular movable conveyor having a plurality of peripherally disposed housing structures each adapted to receive a container having an opening into the interior thereof, a fluid receiver disposed above and movable with said conveyor, means for delivering conditioning fluid to said receiver for supplying the same to said containers, means for delivering said conditioning fluid by gravity flow from the receiver to the exterior and interior of said containers, said last mentioned means including means projecting into said containers through said openings, and means for delivering fluid under pressure adapted to act on said fluid discharged into said containers for dispersing the same over the interior surfaces thereof.

3. In a washing device, the combination of a circular movable conveyor having a plurality of peripherally disposed housing structures each adapted to receive a container having an opening into the interior thereof, a fluid receiver disposed above and movable with said conveyor, means for supplying conditioning fluid, means for heating said conditioning fluid including one or more heating tubes adapted to exhaust spent gases into a flue disposed within the confines of said conveyor, means for delivering said heated conditioning fluid to said receiver for supplying the same to said containers, means for delivering said conditioning fluid by gravity flow from the receiver to the exterior and interior of said containers, said last mentioned means including means projecting through said openings into said containers, and means for delivering fluid under pressure adapted to act on said fluid discharged into said containers for dispersing the same over the interior surfaces thereof, said last-named means having a header disposed in association with said flue whereby the temperature of said air is elevated.

4. In a washing device, the combination of a circular movable conveyor having a plurality of peripherally disposed housing structures each adapted to receive a container having an opening into the interior thereof, said conveyor being adapted to be moved through successive stages of a conditioning cycle for said containers including the washing, draining, rinsing and drying of said containers, means for introducing a continuous jet of air into said containers through the openings thereof, a fluid receiver disposed above and movable with said conveyor, means for delivering conditioning fluid to said receiver for supplying the same to said containers, and means for delivering said conditioning fluid by gravity flow from the receiver at different stages in the cycle of operation of said device to the exterior and interior surfaces of said containers, said last-named means having means for delivering said conditioning fluid into the air stream from said jets of air whereby said fluid is dispersed over the interior surfaces of said containers when introduced therein.

5. In a washing device, the combination of a circular movable conveyor having a plurality of peripherally disposed housing structures each adapted to receive a container having an opening into the interior thereof, said conveyor being adapted to be moved through successive stages of

a conditioning cycle for said containers including the washing, draining, rinsing and drying of said containers, means for introducing a continuous jet of air into said containers through the openings thereof, a fluid receiver disposed above and movable with said conveyor, reservoirs for conditioning fluids for said cycle, means for heating said conditioning fluids and said air, means for continuously delivering said conditioning fluids to said receiver from said reservoirs for supplying the same to said containers, means for delivering said conditioning fluids by gravity flow from the receiver at different stages in the cycle of operation of said device to the exterior and interior surfaces of said containers, said last-named means having means for delivering said conditioning fluids into the air stream from said jets of air whereby said fluids are dispersed over the interior surfaces of said containers when introduced therein, and means for returning said conditioning fluid from said housing structures to said reservoirs.

6. In a washing device, the combination of a circular movable conveyor having a plurality of peripherally disposed housing structures each adapted to receive a container having an opening into the interior thereof, said conveyor being adapted to be moved through successive stages of a conditioning cycle for said containers including the washing, draining, rinsing and drying of said containers, means for introducing a continuous jet of air into said containers through the openings thereof comprising a distributor head and conduits therefrom to each of said housing structures, a fluid receiver disposed above and movable with said conveyor, reservoirs for conditioning fluids for said cycle, means for heating said conditioning fluids and said air including heater tubes disposed within said conditioning fluids having a discharge for spent gases in a flue disposed in association with said distributor head for said air, means for continuously delivering said conditioning fluids from said reservoir to said receiver for supplying the same to said containers, means for delivering said conditioning fluids by gravity flow from the receiver at different stages in the cycle of operation of said device to the exterior and interior surfaces of said containers, said last-named means having means for delivering said conditioning fluids into the air stream from said jets of air whereby said fluids are dispersed over the interior surfaces of said containers when introduced therein, and means for returning said conditioning fluids from said housing structures to said reservoirs.

7. In a washing device, the combination of a circular movable conveyor having a plurality of peripherally disposed housing structures each adapted to receive a container having an opening into the interior thereof, a movable buoyant support in each of said housing structures providing for a normal initial inclined disposition of said containers, said conveyor being adapted to be moved through successive stages of a conditioning cycle for said containers including the washing, draining, rinsing and drying of said containers, means for introducing a continuous jet of air into said containers through the openings thereof, a fluid receiver disposed above and movable with said conveyor, reservoirs for conditioning fluids for said cycle, means for heating said conditioning fluids and said air, means for continuously delivering said conditioning fluids from said reservoirs to said receiver for supplying the same to said containers, means for de-

livering said conditioning fluids by gravity flow from the receiver at different stages in the cycle of operation of said device to the exterior and interior surfaces of said containers, said last-named means having means for delivering said conditioning fluids into the air stream from said jets of air whereby said fluids are dispersed over the interior surfaces of said containers when introduced therein, and means for returning said conditioning fluids from said housing structures to said reservoirs, each of said housing structures having a chamber disposed below said containers forming a part of said fluid return means serving as a reservoir for said conditioning fluids to move said buoyant supports to dispose said containers in substantially upright position during a fluid conditioning operation.

8. In a washing device, the combination of a circular movable conveyor having a plurality of peripherally disposed housing structures each adapted to receive a container having an opening into the interior thereof, a movable buoyant support in each of said housing structures providing for a normal initial inclined disposition of said containers, said conveyor being adapted to be moved through successive stages of a conditioning cycle for said containers including the washing, draining, rinsing and drying of said containers, means for introducing a continuous jet of air into said containers through the openings thereof comprising a distributor head and conduits therefrom to each of said housing structures, a fluid receiver disposed above and movable with said conveyor, reservoirs for conditioning fluids for said cycle, means for heating said conditioning fluids and said air including heater tubes disposed within said conditioning fluids having a discharge for spent gases in a flue disposed in association with said distributor head for said air, means for continuously delivering said conditioning fluids from said reservoirs to said receiver for supplying the same to said containers, means for delivering said conditioning fluids by gravity flow from the receiver at different stages in the cycle of operation of said device to the exterior and interior surfaces of said containers, said last-named means having means for delivering said conditioning fluids into the air stream from said jets of air whereby said fluids are dispersed over the interior surfaces of said containers when introduced therein, and means for returning said conditioning fluids from said housing structures to said reservoirs, each of said housing structures having a chamber disposed below said containers forming a part of said fluid return means serving as a reservoir for said conditioning fluids to move said buoyant supports to dispose said containers in substantially upright position during a fluid conditioning operation.

9. In a washing device, the combination of a circular movable conveyor having a plurality of peripherally disposed housing structures each adapted to receive a container having an opening into the interior thereof, a movable buoyant support in each of said housing structures providing for a normal initial inclined disposition of said containers, said conveyor being adapted to be moved through successive stages of a conditioning cycle for said containers including the washing, draining, rinsing and drying of said containers, means for introducing a continuous jet of air into said containers through the openings thereof, a fluid receiver disposed above and movable with said conveyor, reservoirs for con-

ditioning fluids for said cycle, means for heating said conditioning fluids and said air, means for continuously delivering said conditioning fluids from said reservoirs to said receiver for supplying the same to said containers, means for delivering said conditioning fluids by gravity flow from the receiver at different stages in the cycle of operation of said device to the exterior and interior surfaces of said containers, said last-named means having means for delivering said conditioning fluids into the air stream from said jets of air whereby said fluids are dispersed over the interior surfaces of said containers when introduced therein, means for returning said conditioning fluids from said housing structures to said reservoirs, each of said housing structures having a chamber disposed below said containers forming a part of said fluid return means serving as a reservoir for said conditioning fluids to move said buoyant supports to dispose said containers in substantially upright position during a fluid conditioning operation, and means for vibrating said containers.

10. In a washing device, the combination of a circular conveyor having a plurality of peripherally disposed housing structures each adapted to receive a container having an opening into the interior thereof, means for supplying conditioning fluids, a partitioned receiver disposed above and movable with said housing structures and adapted to receive said conditioning fluids from said means, said receiver having discharge means into the top of said housing structures and additional discharge means disposed within said housing structures and adapted to be received by said containers through said openings, fluid collecting means disposed beneath said housing structures adapted to receive said conditioning fluids therefrom and having discharge means into said conditioning fluid supply means.

11. In a washing device, the combination of a circular conveyor having a plurality of peripherally disposed housing structures each adapted to receive a container having an opening into the interior thereof, means for supplying conditioning fluids, a partitioned annular shaped receiver disposed above and movable with said housing structures and adapted to receive said conditioning fluids from said means, said receiver having discharge means into the top of said housing structure and additional discharge means disposed within said housing structure and adapted to be received by said containers through said openings, a partitioned annular shaped fluid collecting means disposed beneath said housing structures adapted to receive said conditioning fluids therefrom and having discharge means into said sources of conditioning fluids.

12. In a washing device, the combination of a housing structure having an opening for introducing a container into the same and removing said container therefrom, and a support for said container pivotally mounted within said housing structure and normally supporting said container in a position inclined toward said opening, said support having buoyant means operable through the action of fluid within said housing structure to move said support to dispose said container in a substantially upright position.

13. In a washing device, the combination of a housing structure having an opening for introducing a barrel into the same and removing said barrel therefrom, said barrel being adapted to be positioned within said housing structure with its bung-opening lowermost, a support for said

11

barrel pivotally mounted within said housing structure and normally supporting said barrel in a position inclined toward said opening, said support having buoyant means operable through the action of fluid within said housing structure to move said support to dispose said barrel in a substantially upright position, and a fluid discharge means extending upwardly above said support and projecting into said barrel through said bung-opening.
